MIXING TURBINE

James D. Walker, Aurora, Ill., assignor to The American Well Works, Aurora, Ill., a corporation of Illinois

Application April 3, 1939, Serial No. 265,646

7 Claims. (Cl. 261—93)

This invention relates to mixing turbines and has for its principal object to provide a simple and efficient device for mixing chemicals or gas with liquor; and, generally speaking, that object is attained by combining a suitable impeller for the liquor with a valve control tube delivering to the cavitation of the impeller. The feed of the tube merely vents the cavitation and requires no appreciable head loss. The air or other material fed to the cavitation is promptly acted upon by the impeller which breaks it into minute particles and diffuses them evenly through the liquor.

Further objects and advantages of the invention will appear as the description is read in connection with the accompanying drawings illustrating the preferred embodiment of the invention, and, in which

Fig. 1 is a vertical section through a mixing well, equipped with a mixing turbine;

Figs. 2 and 3 are transverse sections taken on the lines 2—2 and 3—3 of Fig. 1;

Fig. 4 is a transverse section of a blade of the impeller taken on the line 4—4 of Fig. 3;

Fig. 5 is a sectional view through the delivery end of one of the air tubes;

Fig. 6 is an outside elevation of the corresponding end of that air tube;

Fig. 7 is a sectional view taken on the line 7—7 of Fig. 1;

Fig. 8 is a transverse section of one arm of the diffuser taken on the line 8—8 of Fig. 7;

Fig. 9 is a plan view of a modified form of mixing well equipped with a mixing turbine; and

Fig. 10 is a vertical sectional view through the mixing well shown in Fig. 9.

But these specific illustrations and the corresponding description are intended for the purpose of disclosure only and are not to be interpreted as placing unnecessary limitations on the claims.

In Fig. 1, 10 indicates the wall of a mixing well having an outlet 11 at one side above an inlet 12 at the other side. Across the top of the well is a bridge 13 upon which the turbine is carried. The turbine unit or apparatus includes a base 14 carrying the driving motor 15 having a shaft 16 connected with impeller shaft 17 by a coupling 18. The bottom of the base 14 is equipped with a broad flange 19 below which is a tubular nipple 20 for connection with a hollow column 21 that depends into the well and carries the suspended mechanism.

The lower end of the column 21 telescopes over and is secured to a cylindrical boss 22 on a cas-

ing head 23 provided with four inlet openings 24 defined by its outer wall 25 and spokes or arms 26.

A cylindrical casing 27 is flanged to the head at 28 and is equipped with a discharge bell 29 directly or through the intermediary of a down-draft tube 30 according to the conditions. In all cases where a down-draft tube will improve the hydraulics, it will be used, otherwise it will be omitted.

The casing is braced to the wall of the well by guys 31, the number and nature of which will depend upon the conditions.

The impeller shaft 17 extends through a bearing sleeve 32 in the casing head 22 and is journaled in ball bearings 33 concentric with the casing 27. Just below the ball bearings the shaft is equipped with an impeller 34 which may vary in construction but preferably has vanes 35 (Fig. 3), the leading edges 36 of which recede from corresponding radii 37 in order to make the impeller self-cleaning. This is especially important where the liquor is to be circulated and includes such fibrous and rubbery material as is ordinarily present in sewage. Vanes of this general kind will propel liquor containing that material without becoming clogged or losing their high efficiency.

The cross section of the vanes 35 will depend upon the hydraulic conditions and the individual ideas of hydraulic engineers, but generally speaking, the form shown in Fig. 4 will be preferred.

Below the impeller is a diffuser 38 composed of four vanes 39 (Fig. 7) shaped as generally indicated in Fig. 8; the exact shape will depend upon the hydraulic conditions for the diffuser serves to straighten out the flow of the liquor, and thus has to be designed in appropriate relation to the impeller.

As will be seen from Fig. 1, the liquor 40 is ordinarily level above the head of the casing 22, thus placing the liquor inlets 24 below the surface. When the impeller is in operation, it produces what is technically known as cavitation in an area above that varies with the speed and the design and other conditions into this cavitation there is placed one or more air pipes 41 supported on brackets 42 and having their lower ends flattened and curved inwardly, as shown at 43 in Figs. 5 and 6. The upper ends of the pipes 41 are equipped with valves 44 here shown as of the familiar conical type having an elongated passage 45 that may be adjusted by rotating the conical body of the valve. In operation the impeller is driven by the motor

15 and sets the liquor in circulation through the casing 27 entering at the inlets 24 and leaving through the outlet or discharge bell 29. The action of the impeller produces a cavitation above it and the tubes 41 deliver to that cavitation. When it is desired to add air or gas, such as CO₂, or chlorine, or such other fluid as it may be desired to mix with the liquor 40, suitable connections are made and the valves 44, or one of them, adjusted to make the feed suited to the conditions. In the case of air, for example, the atmospheric pressure will supply air through the tubes 41 to vent the cavitation and thus deliver it into the liquor just above the impeller which will promptly break it up into very minute particles and disperse it uniformly throughout the stream of liquor passing from the impeller.

While the size, proportions and arrangements will necessarily be a matter of selection and design according to the conditions, the following will indicate satisfactory specifications. A casing 27, twelve inches inside diameter; air pipes 41, one and one-half inches in diameter; and terminating about three inches from the top of the impeller. Other parts are in proportion. These specifications, however, are not intended to suggest limits. Where the speed and design of the impeller, for example, produces a high cavitation, the ends of the air tubes can be raised accordingly without materially altering the operation.

The scheme of operation is to be distinguished from prior devices which cause a high head loss and require a great deal of power to operate, the feed of the air or such like being made by just venting the cavitation formed by the vortex. No appreciable head loss should be necessary, and, therefore, no corresponding increase of power is required, even when air is fed up to one-fourth the capacity of the unit.

Of course, the turbine can be used for a great many mixing and agitating purposes when the air valves are entirely closed. It can be used for aeration and scrubbing alone, for violent agitation and mixing alone, or for a combination of both aeration and mixing. A tremendous amount of circulation per horsepower load is effected because of the low pumping head; and, if desired, the unit can pump or lift the liquor a foot or so.

The turbine can also be used to great advantage in a system where it is desired to have the effluent from a mixing well or the like discharged at a slightly higher level than the influent. This is illustrated in Figs. 9 and 10, Sheet 3, where the well is indicated generally by 50 with the influent at 51 and the effluent at 52, and in Fig. 10 it will be seen that the latter is at a somewhat higher level than the former.

The influent and effluent are separated by what amounts to an influent chamber, defined generally by a wall 53 (Fig. 9) and a bottom 54 (Fig. 10). The wall 53 has a curved portion 55 extending downwardly from the bridge 56 upon which the turbine unit is mounted. The bottom 54 has an opening 57 through which the casing 27 extends into the main body of the well 50.

This arrangement is largely diagrammatical but is sufficient to indicate how the turbine can be used to do all the mixing, etc., heretofore described and also to raise the effluent to a somewhat higher level and still keep the power of consumption well down.

When the influent is less than the capacity of the turbine it is well to provide means to prevent the latter from pumping air. In this in-

stance that result is accomplished by putting a recirculation gate 58 in the curved wall 55 and controlling it with suitable apparatus indicated at 59. By opening the recirculation gate, a suitable amount of flow through the turbine can be kept up to capacity by more or less recirculation determined by the amount of the influent and the opening of the gate.

I claim:

- 10 1. In a mixing turbine, a tubular support member, a shaft rotating within the support member, an impeller on the shaft, a casing surrounding the impeller and including an inlet head carrying the casing and carried by the support member; said impeller being positioned close to said head and said head being substantially open to offer a minimum resistance to the flow of the liquor therethrough to the impeller; and a tube having an inlet exposed to the atmosphere and an outlet positioned to be in the liquor flowing to the impeller on the suction side of the impeller and so close to the impeller as to cause the pressure to be rendered sub-atmospheric solely by direct action of the impeller.
- 15 2. Apparatus for pumping liquor supplied substantially continuously and mixing air therewith, including an inflow chamber to which the liquor is initially supplied, an outflow chamber, a mixing turbine therebetween including an impeller and adapted to draw liquor from the inflow chamber and discharge it into the outflow chamber with sufficient force to raise the level in the outflow chamber higher than the level in the inflow chamber, an air tube open to the atmosphere at one end and delivering within the liquor on the suction side of the turbine and close enough to the impeller to be subjected to the direct suction thereof, and means for permitting a regulated gravitational flow from the outflow chamber back to the inflow chamber to cause a re-circulation of the liquor.
- 20 3. Apparatus for pumping liquor supplied substantially continuously and for aerating the same, including an inflow chamber to which the liquor is initially supplied, an outflow chamber, a mixing turbine therebetween including an impeller and drawing liquor from the inflow chamber and expelling it in the outflow chamber with sufficient force to raise the level in the outflow chamber above that in the inflow chamber, and an open passage between the outflow chamber and the inflow chamber through which liquor will flow back from the outflow chamber to the inflow chamber under influence of the difference in levels in the two chambers, and means associated with the mixing turbine and rendered effective thereby for introducing air into the liquor on the inflow side of the turbine substantially as it enters the turbine.
- 25 4. In a mixing turbine, a tubular support member, a power-driven shaft rotating within the support member and journaled near the bottom thereof, an axial flow impeller on the shaft adjacent the bottom of the support member, adapted to move large volumes of liquor efficiently and uniformly but positioned sufficiently deep in the liquor to prevent the formation of a vortex, and air flow conduit means having an inlet open to the atmosphere, and outlets substantially spaced from the support member and the shaft, symmetrically disposed about the shaft, opening directly into the main stream of liquor flowing toward the impeller, positioned close enough to the impeller on the suction side thereof so that air will be drawn from the out-

let by the suction of the impeller producing the main flow of liquor, and each having a sufficiently small and localized cross section so that the stream of air flowing therefrom will be entrained within the main stream of liquor with substantial uniformity as to point of entrainment and drawn with it substantially uniformly to the impeller while substantially surrounded by liquor and separated by the liquor from the other air streams and while being kept away from the support member and shaft.

5. In a mixing turbine, a tubular support member, a power-driven shaft rotating within the support member and journaled near the bottom thereof, an axial flow impeller on the shaft adjacent the bottom of the support member, adapted to move large volumes of liquor efficiently and uniformly but positioned sufficiently deep in the liquor to prevent the formation of a vortex, a casing surrounding the impeller, having an outlet on the discharge side of the impeller, and an outwardly flaring inlet on the suction side of the impeller, and which is substantially at least as large in diameter at all points between the inlet and the impeller as at the impeller, and air flow conduit means having an inlet open to the atmosphere and outlets substantially spaced from the support member and the shaft, symmetrically disposed about the shaft, opening directly into the main stream of liquor flowing toward the impeller, positioned close enough to the impeller on the suction side thereof so that air will be drawn from the outlets by the suction of the impeller producing the main flow of liquor, and each having a sufficiently small and localized cross section so that the stream of air flowing therefrom will be entrained within the main stream of liquor with substantial uniformity as to point of entrainment and drawn with it substantially uniformly to the impeller while substantially surrounded by liquor and separated by the liquor from the other air streams and while being kept away from the support member and shaft.

6. In a mixing turbine, a tubular support member, a power-driven shaft rotating within the support member and journaled near the bottom thereof, an axial flow impeller on the shaft adjacent the bottom of the support member, adapted to move large volumes of liquor efficiently and uniformly but positioned sufficiently deep in the liquor to prevent the formation of a vortex, a casing surrounding the impeller, having an outlet on the discharge side

of the impeller, and an outwardly flaring inlet on the suction side of the impeller, and which is substantially at least as large in diameter at all points between the inlet and the impeller as at the impeller, and air flow conduit means having an inlet open to the atmosphere and outlets symmetrically disposed about the shaft, opening directly into the main stream of liquor flowing toward the impeller, positioned close enough to the impeller on the suction side thereof so that air will be drawn from the outlets by the suction of the impeller producing the main flow of liquor, and each having a sufficiently small and localized cross section so that the stream of air flowing therefrom will be entrained within the main stream of liquor with substantial uniformity as to point of entrainment and drawn with it substantially uniformly to the impeller while substantially surrounded by liquor and separated by the liquor from the other air streams.

7. In a mixing turbine, a tubular support member, a power-driven shaft rotating within the support member and journaled near the bottom thereof, an axial flow impeller on the shaft adjacent the bottom of the support member, adapted to move large volumes of liquor efficiently and uniformly but positioned sufficiently deep in the liquor to prevent the formation of a vortex, a casing surrounding the impeller, having an outlet on the discharge side of the impeller, and an outwardly flaring inlet on the suction side of the impeller, and which is substantially at least as large in diameter at all points between the inlet and the impeller as at the impeller, and gas flow conduit means having an inlet open to a body of gas and outlets substantially spaced from the support member and the shaft, symmetrically disposed about the shaft, opening directly into the main stream of liquor flowing toward the impeller, positioned close enough to the impeller on the suction side thereof so that gas will be drawn from the outlets by the suction of the impeller producing the main flow of liquor, and each having a sufficiently small and localized cross section so that the stream of gas flowing therefrom will be entrained within the main stream of liquor with substantial uniformity as to point of entrainment and drawn with it substantially uniformly to the impeller while substantially surrounded by liquor and separated by the liquor from the other gas streams and while being kept away from the support member and shaft.

JAMES D. WALKER.
